UNITED STATES PATENT OFFICE

115,334

DESIGN FOR A LENS REMOVER FOR AUTOMOBILE HEADLIGHTS

Otto G. Hildebrand and Gustav Brabenec,
Cleveland, Ohio; said Brabenec assignor to said
Hildebrand

Application June 21, 1938, Serial No. 77,968

Term of patent 7 years

To all whom it may concern:

Be it known that we, Otto G. Hildebrand and Gustav Brabenec, citizens of the United States, residing at Cleveland, in the county of Cuyahoga and State of Ohio, have invented a new, original, and ornamental Design for a Lens Remover for Automobile Headlights, of which the following is a specification, reference being had to the accompanying drawing, forming part thereof,

wherein Fig. 1 is a side elevation of a lens remover for automobile headlights and Fig. 2 is a plan view showing our new design.

We claim:

The ornamental design for a lens remover for automobile headlights, as shown.

OTTO G. HILDEBRAND.
GUSTAV BRABENEC.
